UNITED STATES PATENT OFFICE.

FRANK B. BIGELOW, OF DETROIT, MICHIGAN, ASSIGNOR TO MURPHY IRON WORKS, OF DETROIT, MICHIGAN, A CORPORATION OF MICHIGAN.

SUSPENDED ARCH CONSTRUCTION FOR FURNACES.

Application filed April 9, 1920. Serial No. 372,412.

To all whom it may concern:

Be it known that I, FRANK B. BIGELOW, a citizen of the United States, residing at Detroit, in the county of Wayne and State of Michigan, have invented certain new and useful Improvements in Suspended Arch Constructions for Furnaces, of which the following is a specification.

Improved means for the support and maintaining in position of the arches of furnaces, flat, or otherwise, such as are employed in steam power plants, constitute the subject-matter of the present invention, its leading objects being the supporting of the bricks constituting the arch in such a manner that the supporting means shall be properly protected from the heat of the furnace, shall permit the ready removal and the replacement of one or more of the bricks, and shall assist in distributing some of the air to the combustion chamber if required or desirable.

In order that the attaining of these and other objects by the employment of this invention may be fully understood by those skilled in this art, I have illustrated a desirable embodiment of the same in the accompanying drawings forming a part of this specification and throughout the various views of which like reference characters refer to the same parts.

In the drawings:

Figure 1 is a vertical cross-section through a portion of a furnace of the "Murphy" type with a V-shape grate and opposed fuel-magazines at its opposite sides:

Figure 2 is a vertical section on line 2--2 of Figure 1;

Figure 3 is a plan view of the flat arch and its supporting-means;

Figure 4 is a face view, and Figure 5 an end view of one of the brick hangers.

As is usual in furnaces of this type, there is a pair of oppositely-facing sidewise-feeding fuel-magazines 20 and 21 with the customary coking-plates 22 and 23, coal-pushers or stoking-boxes 24 and 25, and inclined grate-bars 26 and 27 forming the V-shape grate. To the inner sides of the magazines, by means of bolts 28, two brackets 29 and 30 are fastened and disposed lengthwise the furnace, rising above the tops of the magazines as shown in Figure 1.

Resting on and riveted to ledges 31 on the inner faces of these plates are a plurality,

(in the present instance three), of pairs of channel-bars 32 disposed transversely of the furnace, the two of each pair being arranged back to back, that is, web to web, yet spaced apart slightly to receive between them the upper ends of a number of upright, flat, supporting bars or narrow plates 33 secured to the two bars of each pair by rivets 34 through their webs, the lower portions of the plates extending below the bottom flanges of the bars, as shown. These plates are arranged in straight rows lengthwise the furnace and in apertures in their lower ends a plurality of parallel pipes 35 are supported, each pipe extending into an apertured boss 36 in the furnace front-plate 37 and running back to the rear of the arch.

On these pipes or hollow tubes the individual bricks are hung or supported in such a way that if any one or more burns out, replacement can be readily effected. Each brick hanger, as shown in Figures 4 and 5, has a thickened upper portion 38 with a hole 39 therethrough by means of which it is supported on one of the pipes, the pipe extending through the hole, and, in order to permit the hanger to rock in a direction lengthwise of the pipe, the hole is made smallest in the center, flaring somewhat toward both ends. Of course, the hanger can rock crosswise the pipe. It is capable, therefore, of a slight rocking universal movement on the pipe, permitting it to shift as occasion requires by reason of the expansion and contraction of the parts. A web 40 connects the part 38 to a thin elongated foot 41 comprising narrow marginal flanges extended in opposite directions from the lower portion of the web. It is this part which is intended to support a single brick, and for this purpose the top portion of the brick 42 has an undercut groove 43 receiving such supporting foot and a portion of the web. Each brick has its own separate and independent hanger.

As is shown in the various figures, each pipe supports a number of these hangers and their bricks, the former being spaced apart on the pipe by sleeves or collars 44. The forward brick of any longitudinal row is in engagement with the wall or lining 45 (Figure 2) at the front of the furnace, and the rearmost brick 46 of special shape extending upwardly over the back end of the corresponding pipe is held from displace-

ment by a bolt or pin 47 extending transversely through the pipe just back of the last hanger acting as a stop or abutment. The bricks may expand and contract under changes of temperature and shift their positions slightly when heated returning to normal position by gravity when cooled.

The arch-plate bricks 48 are of special construction, being grooved at 49 for the reception of the longitudinal arch-plate rib 50 and socketed in their upper portions for 10 the accommodation of supporting shoes 51 hung on pipe 51^a carried by longer bars 51^b, thus positioning these side bricks below the 15 arch proper, portions of the bricks underlying the arch as is clearly shown in Figure 1. These pipes or tubes 51^a may likewise be equipped with spacing spools or sleeves 51^c and the sockets or recesses in the 20 tops of the bricks do not extend all the way across the bricks, otherwise the hangers would be exposed to the action of the fire.

The upstanding part of each rearmost brick 46 is provided with a hole 52 in register or alignment with the corresponding pipe, these holes being ordinarily closed by batches or plugs of fire-clay 53. Above these bricks the back portion of the furnace is closed by bricks 54 supported on a plate 55 secured to the back pair of hanger bars 32. 25 Above the latter the furnace is closed by one or more readily-removable cover-plates 56.

The space above the arch-bricks at the front part of the furnace is divided into 30 longitudinal sections by a pair of partition walls 60 and 61 (Figure 3), extending rearwardly of the furnace from the front-plate. Each of these walls may be composed conveniently of one or more suitably-shaped 35 sheet-metal plates. Between the partitions 60 and 61, the furnace front-plate 37 is apertured at 62 at one or more places, for the entrance of the outside air.

A portion of the air for combustion enters the furnace through the opening or 40 openings 62 and in passing rearwardly over the arch becomes heated. When such air reaches the inner ends of the partition walls 60 and 61, it passes around them and enters 45 the combustion chamber through the spaces or flues between the arch-plates and the side-bricks 48. Another portion of the air enters 50 the front of the furnace through apertures in register with the cold-air boxes or flues 55 beneath the coking-plates 22 and 23 and is more or less heated in its traverse through the conduits. It then passes upwardly 60 through passages 63, 63, (Figure 1), back of the rear-walls of the magazines, into the 65 space above the arch, from which it in turn enters the combustion chamber between the ribs on the arch-plates in the customary manner. It should be observed furthermore, 70 that an additional portion of the air enters 75 the furnace and passes through the plural-

ity of pipes 35, being delivered through the rear ends of the pipes to the back portion of the furnace above the arch, from which place it flows in the usual manner down into the combustion chamber. Obviously, by such passage of the air, these supporting tubes or pipes are maintained cool and prevented from injury and damage by reason of excessive heat, and at the same time, air is discharged into a desirable portion of the 75 furnace construction.

In some instances, it may be desirable to perforate one or more of the supporting-pipes and its spacing collars or sleeves as partly indicated at 64 in Figure 3. By 80 proper spacing of these apertures or air discharge holes any suitable and desirable distribution of the air in the space above the arch may be secured, and at the same time, such air will be employed to perform 85 the cooling function of the supporting pipes themselves. In Figure 3 I have shown only a few of the pipes as perforated, but it is to be understood that any number of them may be so constructed and the holes may be 90 located and spaced as seems the best.

Assuming that one of the bricks 42 has become damaged sufficiently to require replacement, the old brick is removed and a new one put in place in the following manner. The plug of fire-clay 53 is taken out and the retaining-pin 47 is removed. Then a follower rod of substantially the same caliber as the exterior of the pipe is placed in alignment with the pipe through the hole 52 and pushed forwardly, carrying the pipe with it, the pipe protruding through the furnace front-plate as will be readily understood. Inasmuch as the rod directly follows the end of the pipe all of the bricks 100 will remain properly supported. The rear end of the pipe is pushed through the aperture of the injured brick hanger or support and then the rod is retracted slightly, leaving a small gap between the pipe and rod, 110 thus freeing the hanger of the damaged brick from the support and thus permitting the removal of such brick and hanger. To facilitate in displacing the brick when thus released, one or more of the cover or top 115 plates 56 may be temporarily taken off, thus giving access to the brick and hanger from above.

As soon as the new brick and hanger are in place, the pipe is pushed rearwardly, 120 carrying the supporting or follower rod with it, thus engaging the hanger of the new brick as well as all the other aligned hangers as in the original condition of things. The rod of course, passes rearwardly out 125 through the hole 32 which may again be plugged up. The cross-pin 47 is also put in place. In this way any one or more bricks may be replaced, the arch-plate bricks being manipulated in much the same way during 130

change of bricks. The follower rod acts as a temporary support for the bricks and maintains their hangers in register ready to again receive the supporting pipe. As is obvious, the sleeve assists in keeping the pipe and rod in alignment. The beveling of the holes in the hangers facilitates inserting of the rod or pipe as well as permitting a possible rocking movement of the hangers on the pipe.

To those skilled in this art it will be clear that many minor mechanical changes may be made in the structure described and illustrated without departure from the heart and essence of the invention and without the sacrifice of any of its substantial benefits and advantages. For example, the brackets, 29, 30 may be cast on or bolted to the arch-plates of the inner walls of the magazine and the panel-bars 32 need not be necessarily riveted or otherwise fastened to the ledges 31.

I claim:

In an arch-construction of the character

described, the combination of a plurality of arch-bricks, a main supporting-structure, a hollow supporting-member slidably mounted on said structure, a furnace front-plate apertured in registration with said member, the latter being adapted to receive outer air through said front-plate aperture and deliver it into the space above the arch, a plurality of hangers supporting said bricks individually from said member, a back wall for the space above the arch apertured in register with said member and removable means normally closing said back wall aperture, the construction permitting the removal of any hanger and its injured brick by shifting the member longitudinally sufficiently through one of said apertures to free the hanger of the injured brick therefrom and temporarily supporting the remainder of the bricks not sustained by the member in its new position by a follower introduced through the other aperture.

FRANK B. BIGELOW.
